MANIFOLDING MEANS FOR TYPEWRITERS

Raymond L. Gillson, Cincinnati, Ohio

Application May 2, 1932, Serial No. 608,636

8 Claims. (Cl. 197—126)

This invention relates to manifolding means for typewriters.

An object of the invention is to provide typewriter attachment means performing the function but eliminating the use of the commonly utilized carbon paper.

Another object is to provide such means readily attachable to the most generally used forms or makes of typewriter without alteration of the machines.

Another object is to produce means of this kind adapted to produce superior results at a lessened cost.

Another object is to provide an improved holding means for an ink transfer ribbon or the like.

Another object is to provide manifolding means which are simple in manufacture and in use.

These and other objects are attained by the means described herein and illustrated in the accompanying drawings, in which:

Fig. 1 is a front elevational view of a typewriter platen and carriage with means of the present invention associated therewith, parts being broken away.

Fig. 2 is a top plan view of the same.

Fig. 3 is a cross sectional view taken on line 3—3 of Fig. 1.

Fig. 4 is a diagrammatic end view of a platen with sheets of paper, holding means therefor, and ink transfer ribbons of this invention associated therewith.

Figs. 5 to 9 inclusive are detail views of parts of the present invention.

The parts of a typewriter illustrated, with which the means of this invention are adapted to be associated, comprise the platen 12 mounted upon a shaft 13 between the sides 14 and 15 of a platen carriage, the platen being rotatable by means of a thumb wheel 16.

The manifolding means of this invention comprise a bracket 17 adapted to be readily positioned upon one of the sides 15 of the platen carriage by the screws normally provided thereon. As illustrated, the bracket is adapted to be positioned on the outside face of carriage side 15 by means of screws 18 passing through perforations 19 (Fig. 6) into the carriage. In addition, the bracket here shown is provided with a large perforation 20 through which the end of the platen shaft 13 is adapted to pass. Any other attachment means may be utilized. Moreover, in some makes of typewriter, it may be more desirable to mount the bracket on the top rather than on the side face of the carriage side. The

shape of the bracket may be modified to meet such requirements.

Bracket 17, at its outer end is provided with an ear 21 extending inwardly of the carriage and parallel with the platen. Strip-like bars 22 are pivotally connected by means of extensions 24 to said ear, as at 23, for pivotal movement in a vertical plane. Bars 22 may be of angle-strip shape, that is of L-shape cross section to permit nesting of the bars one upon the other. These bars are adapted in operative position, to extend across to the opposite side 14 of the platen carriage, forwardly of and in spaced relationship with the platen. At their free ends bars 22 may be notched, as at 25, (Fig. 5) to be readily engaged by a spring clip 26 vertically mounted as at 28 (Fig. 3) on a finger 29 which in turn is secured upon a lug 30 attached to side 14 of the carriage. Clip 26 is provided with notches 27 adapted one each to receive one of said free ends 25 of the bars. The clip is resiliently retained in engagement with the bar ends by means of a spring 31. Any other suitable means for holding the free ends of bars 22 may be utilized.

Each bar 22 has at each end thereof an arm 32 and 33. Arm 33 may be integral with bar 22, as shown. Arm 32 is a separate member formed at one end with a sleeve 34 adapted to slidably embrace bar 22 (Fig. 3). The outer portions of said arms are turned downwardly as at 35 and 30 their free ends are formed into spindles 36.

Spindles 36 are each adapted to hold an end of an ink transfer ribbon 37. By slidable movement of arm 32 along its bar, the ribbon can be rendered taut for use or loosened for removal. A shifting tab 40 may be provided on the bottom of sleeve 34. In operative condition, the ribbon is adapted to extend adjacent the platen in upright position as to its width and in the line of the type strokes of the typewriter. In order that a plurality of the manifolding ribbons may be utilized, the distances between the arms 32 and 33 of each pair are progressively diminished whereby one pair is embraced by the next pair. And in order that the ribbons 37 may be operatively positioned one behind the other, the pairs of arms 32 and 33 are progressively diminished in length. The foregoing structure is clearly seen in Fig. 3.

It will further be seen that the adjacently disposed arms 32 and 33 rest one upon the other. In order to support the outermost pair of arms, the lug 30 extends outwardly, as at 38 (Fig. 2) beneath the arm at that side, and at the other side, the outermost arm is adapted to rest upon a stud 55

39 (Figs. 2 and 6) struck from the body of bracket 17, or upon some similar support means.

The bars 22 are adapted to be pivotally moved into operative position through a vertical plane 5 extending transversely of the typewriter. At this time, the sheets 41 (Fig. 4) placed in a typewriter are adapted to be held apart to permit entry of a ribbon between each pair of sheets. Each ribbon is then in position to transfer typed impressions from the outer to the inner of two sheets. When it is desired to remove the ribbons from operative position, the bars 22 are swung outwardly of the carriage side 15 and are there adapted to be disposed against a support strip 42 (Figs. 15 1 and 2) having guides 43 thereon.

A modified bar structure is seen in Fig. 7. Herein a separate pivot plate 45 is substituted for the integral bar extension 24 seen in Fig. 5. Plate 45 is adapted to be pivotally mounted on ear 21 and is provided with a pair of adjacently disposed resilient flanges 51 adapted to slidably receive between them and resiliently hold the end portion 52 of bar 44. End portion 52 is formed with an aperture 49 adapted to receive the resiliently contacting studs 47 provided on flanges 51 whereby the bar may be "snapped" into operative position. By this means, bars 44 may be instantaneously placed in and removed from operative association with pivot plate 45. It will be understood that a desirable number of said pivot plates may be pivotally mounted on the same axis on ear 21, in overlying relationship one with another.

In Fig. 8, the ribbon 37 instead of being simply looped at its ends, as in Fig. 5, is there provided with a clip 48, adapted to have one end portion 49 doubled upon an end of the ribbon, and another bent portion 50 slightly spaced from the ribbon to permit insertion of the holding spindle 36.

It is obvious that the operation is simple and that one or a plurality of the ribbons may be utilized in accordance with manifolding requirements. The resulting typed impressions are strong and clear. One of the ribbons is adapted to long outlast a sheet of carbon paper.

What is claimed is:

1. Manifolding means for typewriters and comprising a bracket adapted for attachment on one side of the platen carriage of a typewriter, a plurality of angle bars adapted to be disposed in nested relationship and mounted each by one of its ends on said bracket for pivotal movement through a vertical plane, each bar in operative position being adapted to extend across said carriage forwardly of and in spaced relationship with the platen, means on the carriage for releasably holding the free ends of the operatively positioned bars, a pair of arms disposed one adjacent each end of the bars, the arms of said pairs being spaced apart progressively diminishing distances whereby one pair is embraced by the preceding pair, the adjacently disposed arms being adapted to rest one upon the other, means on the carriage for supporting the outermost of said arms in the operative position of the associated bar, and an ink transfer ribbon held by the outer ends of each pair of arms and adapted each in the operative position of said bars to extend taut and upright as to its width adjacent the platen and in the line of the type strokes of the typewriter, the arms of each pair being movable relative to one another to permit positioning, tightening and removal of the associated ribbon, said pairs of arms being of successively diminish-

ing length whereby the ribbons may be disposed one behind the other and each ribbon being adapted to be moved by means of its associated bar into and out of position between two sheets held by the typewriter and to transfer typed impressions from the outer to the inner of said sheets.

2. Manifolding means for typewriters and comprising a bracket adapted for attachment on one side of the platen carriage of a typewriter, a bar mounted by one of its ends on said bracket for pivotal movement through a vertical plane, said bar in operative position being adapted to extend across said carriage forwardly of and in spaced relationship with the platen, means on the carriage for releasably holding the free end of the operatively positioned bar, an arm at each end of the bar, means for supporting the arms in the operative position of the bar, and an ink transfer ribbon held by the outer ends of said arms and adapted in the operative position of said bar to extend taut and upright as to its width adjacent the platen and in the line of the type strokes of the typewriter, one of said arms being movable to permit positioning, tightening and removal of the ribbon, said ribbon being adapted to be moved by means of said bar into and out of position between two sheets held by the typewriter and to transfer typed impressions from the outer to the inner sheet.

3. A device for holding an ink transfer ribbon or the like and comprising a strip-like bar, a pair of arms on the bar, one adjacent each end thereof, and a sleeve on one of said arms and slidably embracing the bar for associating the arm with the bar, the outer ends of said arms being adapted each to hold one end of the ink transfer ribbon, and the slideable arm being adapted to be moved along the bar for stretching the ribbon taut and to be held in its given position by leverage action of the stretched ribbon thereon.

4. Manifolding means for typewriters and comprising a plate pivotally mounted at one side of the platen carriage of a typewriter and provided with a pair of resilient flanges, a bar adapted to be inserted at one end between and removably held by said resilient flanges, said bar in operative position being adapted to extend across said carriage in spaced relationship with the platen, means on the carriage for supporting the free end of the operatively positioned bar, an arm at each end of the bar, and an ink transfer ribbon held taut by said arms and adapted in the operative position of said bar to extend upright as to its width adjacent the platen and in the line of the type strokes of the typewriter, said ribbon being adapted to be moved by means of said bar into and out of position between two sheets held by the typewriter and to transfer typed impressions from the outer to the inner sheet.

5. Manifolding means for typewriters and comprising a bracket adapted for attachment on one side of the platen carriage of a typewriter, an ear projecting from said bracket, a plate pivotally mounted on said ear and provided with a pair of resilient flanges, a bar adapted to be inserted at one end between and removably held by said resilient flanges, said bar in operative position being adapted to extend across said carriage in spaced relationship with the platen, means on the carriage for supporting the free end of the operatively positioned bar, an arm at each end of the bar, and an ink transfer ribbon held taut by said arms and adapted in the operative position of said bar to extend upright as to its width adjacent the platen

and in the line of the type strokes of the typewriter, said ribbon being adapted to be moved by means of said bar into and out of position between two sheets held by the typewriter and to transfer typed impressions from the outer to the inner sheet.

6. Manifolding means for typewriters and comprising a bar adapted to be pivotally mounted by one end on the platen carriage of a typewriter, the bar in operative position being adapted to extend across the carriage in front of the platen, a pair of spaced arms on the bar, an ink transfer ribbon held by said arms and adapted in the operative position of the bar to extend taut and upright as to its width adjacent the platen between two sheets positioned on the typewriter and in the line of the type strokes, and means providing for relative movement between the arms to permit positioning, tightening and removal of the ribbon.

7. Manifolding means for typewriters and comprising a bar and means for pivotally mounting the bar on the platen carriage of the typewriter, said bar in operative position being adapted to extend across said carriage forwardly of and in spaced relationship with the platen, a pair of spaced arms on the bar, means for supporting the arms in the operative position of the bar, an ink transfer member held by said arms and adapt-

ed in the operative position of said bar to extend taut and upright as to its width adjacent the platen and in the line of the type strokes of the typewriter, and means providing for relative movement between the arms for effecting adjustment of the transfer member, said member being adapted to be moved by means of said bar into and out of position between two sheets held by the typewriter and to transfer typed impressions from the outer to the inner sheet.

8. The combination with a typewriter, of multiple manifolding means, said means comprising a plurality of bars each pivotally mounted at one end on one side of the platen carriage of the typewriter, said bars being adapted in the operative position to extend across the carriage in front of the platen, a pair of spaced arms on each bar, and an ink transfer member stretched between each pair of arms and adapted each to be positioned between two sheets operatively associated with the typewriter whereby a plurality of manifold copies may be produced on the typewriter, the bars and the transfer members associated therewith being adapted to be swung laterally of the carriage into an upwardly extending non-operative position.

RAYMOND L. GILLSON.
